1

This invention relates to apparatus for inserting into contact with one or more main printed webs of a printing press page forming sheets cut from a pre-printed web, and more particularly concerns apparatus of this nature for inserting such cut sheets in accurate page registry with the page forming sheet lengths of the main web.

High quality multi-color printing, which requires accurate registry of successive printings of the same illustration in different colors, cannot be obtained at the high web speeds at which modern newspaper presses operate. Newspapers are desirably made up of a plurality of single color or black and white sheets consolidated with a lesser number of multi-color sheets. Accordingly, a newspaper containing some high quality multi-color sheets could be produced by pre-printing the multi-color portion at the low speed requisite to high quality, then rewinding the pre-printed web into a roll, and thereafter combining the pre-printed web from the rewound roll with the high speed single color web or webs. Such combining presents the problem of maintaining registry between the inserted pages of the pre-printed multi-color web and the pages of the single color webs while the webs are travelling at the high speeds customary or requisite in modern single color newspaper presses. Even though the page forming sheet lengths of the multi-color web are, when printed, of uniform size, the web length may, and usually does, change due to loss or gain of moisture or other causes during rewinding, storage, and unwinding before the webs are combined, and such changes usually are not uniform throughout the rewound web length. If the pre-printed web is fed at a constant speed, such changes in its length change the position of the printed page relative to the adjacent printed page of the main or single color web or webs. Due to the high speed at which the webs travel, any difference in page forming sheet length between the pre-printed and main webs produces a rapidly multiplying lack of page registry which cannot be effectively corrected by previously known means without tearing of the web.

Mechanism is known for maintaining webs in registry by the use of light responsive means governing web speed varying means. When such mechanism is applied to an arrangement in which separate sheets are cut from one web and consolidated with another, there remains the problem of cutting the sheets from the pre-printed web and consolidating them with the main web or webs without tearing or buckling the inserted

2

sheets as a consequence of the changes in the speed of travel of the pre-printed web that keep it in page registry with the main webs.

It is the object of the present invention to provide apparatus that inserts or combines with a high speed main web or webs, sheets cut from a pre-printed and rewound web while maintaining page registry between the inserted sheets and main webs and without tearing or buckling the inserted sheets or the pre-printed web from which they are cut. According to the invention, this is accomplished by feeding the pre-printed web at a velocity that is variably controlled to correspond, page for page, with the velocity of the main web or webs, and cutting page forming sheets from the pre-printed web and combining them with the main web or webs while maintaining such sheets under suitable tension regardless of whether their rate of travel is at the moment of cutting being retarded or accelerated to maintain page registry. The variable web speed control may be obtained by the use of known mechanism referred to above which scans register marks disposed in predetermined relation to printed pages on the pre-printed web, compares such scannings with scannings of means representing the positions of the main web pages, and speeds up or slows down the pre-printed web feeding mechanism sufficiently to maintain the page registry required. A cutting couple, driven in timed relation with the main web printing mechanism, cuts sheets from the speed regulated pre-printed web and includes a transfer cylinder with pins on its surface for piercing and so engaging the pre-printed web to carry it along the peripheral surface to the point where the sheet is cut from it. Means are provided for driving the transfer cylinder at a peripheral velocity slightly in excess of the highest linear velocity to which the pre-printed web is accelerated in maintaining page registry so that the web piercing pins on the transfer cylinder advance relative to the web before it is cut and maintain it under tension, tearing small slits in this web as a consequence of such advance. The length of these slits varies when the speed of the pre-printed web is varied to keep the printed pages thereon in registry with the pages of the main web or webs. The increase in surface speed of the transfer cylinder over the maximum speed at which the pre-printed web is driven is preferably produced by making this cylinder somewhat longer in sheet carrying peripheral length than the page forming sheet lengths of the pre-printed web. In other words,

the periphery of the transfer cylinder is slightly longer than the maximum length of pre-printed web fed by the variable speed feeding means during each revolution of the transfer cylinder.

I have found that if the peripheral length of each sheet carrying section of the transfer cylinder is approximately one-fourth of one percent to one and one-half percent longer than the standard page forming sheet length at which the pre-printed web was originally printed, the foregoing result is accomplished. With this arrangement, the pins on the transfer cylinder always maintain the pre-printed web under tension regardless of the acceleration or deceleration of the pre-printed web by the variable web speed control means incident to maintaining page registry.

In accordance with one aspect of the invention, the page forming sheets cut from the pre-printed web are removed from the transfer cylinder by a pin carrying collecting cylinder and are thereon consolidated with the main web or webs and also engage the collecting cylinder. The pins on the collecting cylinder stab both the pre-printed web sheets and the main web or webs and tear out of these webs, thus forming torn tabs that lock the sheets cut from the pre-printed web to the main web or webs to prevent displacement of the cut sheets from page registry as the consolidated sheets and webs pass to the folder.

In some cases, the page forming sheet lengths of a pre-printed color web may be slightly shorter than the page forming sheet lengths of the main single color web or webs with which sheets from the pre-printed web are to be combined. Such short sheet lengths can be handled by my improved apparatus by reducing the peripheral dimension of the transfer cylinder in proportion to the reduction in page forming sheet length of the pre-printed web below the page forming sheet length of the main web or webs while still maintaining that peripheral dimension large enough to provide a transfer cylinder surface speed slightly greater than the maximum speed to which the pre-printed web is accelerated in maintaining page registry. This reduction in transfer cylinder periphery lowers the linear velocity of the sheets carried thereby, but the collecting cylinder that receives the cut pre-printed sheets from the transfer cylinder operates at a surface velocity equal to the main web speed and so accelerates the cut sheets to that speed as they are removed from the transfer cylinder.

In the foregoing general discussion of the invention and in the following specific description of embodiments thereof, the pre-printed web is frequently referred to in the singular and in many cases only one web is employed for this purpose. It is, however, within the scope of the invention to insert two or more superimposed sheets cut from superimposed portions of a pre-printed web, and a typical arrangement for accomplishing this will be described. The term "pre-printed web" as used herein embraces such superimposed pre-printed web portions.

In describing the invention in detail, reference will be made to the accompanying drawings, in which:

Fig. 1 is a diagrammatic and simplified elevation of apparatus embodying the invention and associated web printing and feeding apparatus;

Fig. 2 is an enlarged elevation, partly in section, of the sheet cutting and inserting mechanism of the apparatus shown in Fig. 1;

Fig. 3 is a plan view of the mechanism shown in Fig. 1;

Fig. 12 is an elevation of the apparatus shown in Fig. 11.

Referring to the drawings, I have illustrated in diagrammatic form two printing units A and B of known construction, each comprising impression cylinders 1 and 2 cooperating with plate cylinders 3 and 4, by means of which successive pages are printed on both sides of the respective main webs 5 and 6.

A rewound web roll 7 comprises the pre-printed web 8 which has been pre-printed at relatively low speed, preferably in two or more colors, in order to obtain high quality color printing. When originally printed, this web had a fixed and standard page forming sheet length which is designated *a* in Fig. 8. Because of the absorption or loss of moisture and other causes, the page forming sheet length of the pre-printed web 8 delivered from the roll 7 varies slightly throughout the web length from the standard length at which it was originally printed, and these variations result in slightly overlength and underlength sheet lengths at different parts of this web. The pre-printed web 8 has register marks 45 printed along one margin, and in the disclosed embodiment there are three such register marks for each page forming sheet length of this web.

The several impression and plate cylinders of the printing units A and B are driven in synchronism, as is customary, from a common driving element, here illustrated as a power driven shaft 9 connected to the two printing units through bevel gears 10 and 11 and vertical shafts 12.

The main web 5 printed in the unit A passes over rollers 14 and 15, around a part of the surface of a collecting cylinder 16, under the rollers 17 and then between the drag roller 18 and propeller roller 19 onto a conventional former 20. The main web 6, printed by the unit B, passes over the rollers 21, 22, 23, 24 and 25, then onto the surface of the collecting cylinder 16, under the roller 17 and so between the drag roller 18 and propeller roller 19 onto the former 20.

The pre-printed web 8 runs from the roll 7 over the rollers 26, 27 and 28, through the feeder 75 F between the driven roller 29 and pressure roller

30, around the roller 30 under the driven roller 31 thereof and onto the surface of the transfer cylinder 33 against which the web is passed by a spring pressed roller 34. The pre-printed web feeder F is driven from the main printing unit drive shaft 9 through bevel gears 35 and 36, shafts 37 and 38, a differential gear unit 39, shaft 40, bevel gears 41 and a spur gear 42 which engages gears 43 and 44 on the shafts of the driven rollers 29 and 31 (Figs. 1, 2 and 3). The differential gear unit 39 forms a part of a known mechanism for varying the speed at which the pre-printed web is fed in order to maintain page registry between the pre-printed web 8 and the main webs 5 and 6, as is hereinafter explained.

As the pre-printed web 8 passes between the rollers 31 and 32, its marginal portion where the register marks 45 are located is scanned by a scanner S of known construction comprising essentially a light source 46 and a photo-cell 47 to receive light reflected from the source 46 by the web 8. With this arrangement, impulses are received by the photo-cell 47 when each of the register marks 45 on the pre-printed web pass the scanner. The scanner S is preferably mounted for adjustment longitudinally of the web 8 by means of a fixed bar 48 on which the scanner slides and a feed screw 49, threadedly engaging the scanner and rotatable by a hand wheel 50. The scanner S forms a part of a known page registry maintaining mechanism.

A cutting couple comprising the transfer cylinder 33 and a cooperating cutting cylinder 51 cuts successive page forming sheets from the pre-printed web 8. The transfer cylinder 33 shown has two resilient cutting blocks 52 and 53 at diametrically opposite points in its peripheral surface and a knife 54 on the cutting cylinder 51 cooperates successively with these blocks to cut sheets from the web 8. The cutting cylinder 51 is half the size of the transfer cylinder 33 and rotates at twice the angular velocity of the transfer cylinder and thus at the same peripheral velocity of the transfer cylinder. The transfer cylinder 33 is provided with two sets of web engaging pins 55 and 56 of known construction which are operated by a stationary cam 57 adjacent one end of the cylinder through cam engaging rollers 58-59', crank arms 59-59', shafts 60-60' and arms 61-61'. The shape of the cam 57 is such that each set of pins 55 and 56 is extended to pierce and so engage the web 8 at approximately the point X (Fig. 4) and is withdrawn to disengage the sheet cut from this web at approximately the point Y. The collecting cylinder 16 is provided with one set of sheet engaging pins 62 operated by a stationary cam 63 through a roller 64, an arm 65, a shaft 66 and arms 66'. The collecting cylinder pins 62 are extended to pierce the main web 5 and the sheet cut from the pre-printed web 8 at approximately the point Y in Fig. 4, the ends of the extended pins 62 extending into grooves 67 in the cylindrical surface of the transfer cylinder 33, as shown in Fig. 5. The pins 62 are not retracted until approximately the point indicated at Z in Fig. 4, so that these pins tear small tabs from the superimposed webs 5 and 6 and the interposed sheet cut from the pre-printed web 8, as shown at 110 in Fig. 6. The construction of the web engaging pins of the transfer cylinder 33 and the collecting cylinder 16 is known in the art and is disclosed, for example in Patent No. 1,834,666.

The cutting cylinder 51 and the collecting cyl-

inder 16 are driven in timed relation through the gears 68, 69 and 70 (Fig. 3), the gear 69 being fixed to the shaft of the transfer cylinder 33. The transfer cylinder 33 is driven from the main drive shaft 9 through a suitable driving connection illustrated as the bevel gears 71, the shaft 72, the differential gear unit 73, the shaft 74 and the bevel gears 75. The arrangement is such that the transfer cylinder 33 and its associated cutting and collecting cylinders turn at an angular velocity which is in step, page for page, with the page forming sheet lengths of the main webs 5 and 6, printed in the units A and B. Thus, for each page forming operation of the units A and B, the transfer cylinder 33 makes a half revolution and the cutting and collecting cylinders 51 and 16 make one revolution.

In accordance with the present invention, means are provided for driving the transfer cylinder 33 at a surface speed or peripheral velocity slightly in excess of the highest linear velocity at which the pre-printed web 8 is propelled by the feeder F. The feeder F is driven, as hereinafter described, by known mechanism that accelerates and decelerates the pre-printed web slightly to compensate for variations in its page forming sheet length, so as to maintain page registry between sheets cut from this web and the main webs 5 and 6. I have found that if the periphery of the transfer cylinder 33 is from one quarter of one percent to one and one-half percent longer than the length a of the page forming sheet lengths it carries as originally printed and before variations in length occur, then the peripheral velocity of the transfer cylinder will always be slightly in excess of the linear velocity of the pre-printed web 8 despite acceleration of this web by the feeder F to keep it in page registry with the main webs 5 and 6. Since the transfer cylinder 33 carries two sheet lengths on its periphery, this means that the entire periphery of the cylinder 33 is one-quarter of one percent to one and one-half percent longer than twice the original page forming sheet length of the pre-printed web 8 before it has shrunk or elongated. With this construction, the length a_1 (Fig. 9) of each sheet carrying portion of the transfer cylinder is slightly longer than the page forming sheet length a (Fig. 8) of the pre-printed web 8 as originally printed and is longer than the maximum length of pre-printed web fed by the feeder F during each half revolution of the transfer cylinder. Thus, although the transfer cylinder 33 operates in synchronism page for page with the main webs 5 and 6, its peripheral surface always moves at a slightly greater speed than the pre-printed web 8. As the web 8 is carried around the surface of the cylinder 33, the pins 55 and 56 tear small slots in the leading marginal edge of each sheet until it is cut from the web. These slots do not impair the finished product because they do not enter the printed portion of the page. The described arrangement maintains the pre-printed web 8 always in tension even while it is being accelerated to maintain page registry with the main webs 5 and 6.

The differential gear unit 73 is provided to permit initial setting of the cutting couple, including the transfer cylinder 33, in page registry with the main webs 5 and 6 so that sheets delivered thereby from the pre-printed web 8 will be disposed in registry with the pages of the main webs. This differential gear unit is of known construction having a bevel gear 76 secured to the drive input shaft 72 and engaging the bevel gears 77

and 78 rotatably carried in the ring or differential member 79 which also carries a worm gear 80. The bevel gears 77 and 78 engage a bevel gear 81 fixed to the output shaft 74. A worm 82 driven by a motor 83 engages the worm gear 80. The motor 83 may be energized to turn in either direction by suitable reversing switches, here illustrated as push button switches 84 and 85. When the motor 83 is deenergized, the shafts 72 and 74 turn in unison at the same speed and if it is necessary to advance or retard the position of the cutting couple relative to the pages of the main webs 5 and 6, this may be done by operating the motor 83 in the proper direction to advance or retard the shaft 74 with relation to the shaft 72.

The differential gear unit 39 acts to vary the speed of the pre-printed web feeder F so as to maintain the page forming sheet lengths of the web 8 in registry with the cutting couple and so in registry with the pages of the main webs 5 and 6, which move in timed relation with the cutting couple. The differential gear unit 39 illustrated is of conventional construction having an input bevel gear 86 fixed to the power input shaft 38 and engaging the bevel gears 87 and 88 rotatably carried by the ring or differential member 89. The bevel gears 87 and 88 engage the output bevel gear 90 fixed to the output shaft 40. A worm gear 91 on the differential member 89 is engaged by a worm 92 driven by a correction motor 93.

The differential gear unit 39 forms a part of a known mechanism for varying the speed of a web to maintain it in registry with another web or with a cutting couple despite minor variations in the length of the web. This mechanism is here illustrated as made up of the above-described differential gear unit 39, the web register mark scanner S, a selector mechanism L including a disc 94 secured to or driven by the shaft of the transfer cylinder 33 and disc scanning mechanism associated therewith, a pilot generator 95 driven at a speed proportional to that of a transfer cylinder, and a control mechanism panel 96. Because this mechanism is known and does not per se comprise the present invention, it will be described herein only generally.

Referring to Figs. 2, 9 and 10, the disc 94 of the selector mechanism L contains six pairs of slots 97-98, each pair corresponding to one of the three register marks 45 on each page forming sheet length of the pre-printed web 8. The outer slots 97 are aligned with a stationary photo-cell 99 having a light admitting slit or aperture 100, and the inner slots 98 are aligned with a stationary photo-cell 101 having a light admitting slit or aperture 102. A light source 103 directs light through disc slots which control the admission of light to the photo-cell apertures. The adjacent ends of the slots 97 and 98 of each pair are on the same radial line of the disc 94 and the apertures 100 and 102 of the respective photo-cells are slightly displaced circumferentially of the disc, so that as each pair of slots passes the photo-cells, there is a so-called dead zone at which no light is admitted to either photo-cell.

The pilot generator 95 is driven by suitable means, such as a chain 104 and sprockets 105 and 106, from the shaft 74 that drives the transfer cylinder 33. This generator supplies energy for operating the correction motor 93 of the differential gear unit 39. The correction motor 93 runs continuously in one direction at a speed that maintains the pre-printed web feeder F at such a speed as to feed the web 8 at the same linear velocity as the main webs 5 and 6 until correction

is required, whereupon the speed of the correction motor 93 is increased or decreased by means of a correction factor applied to the field excitation of the pilot generator 95. The correction factor is derived by a comparison in time between an impulse obtained by the scanner S from a register mark 45 on the web 8 with impulses received from one or the other of the photo-cells 99 or 101 of the selector mechanism L.

The control mechanism of the panel 96 receives impulses from the photo-cell 47 of the web scanner F and from the photo-cells 97 and 101 of the selector mechanism L. It operates in a known manner such that unless simultaneous impulses are received from both the web scanning photo-cell 47 and one only of the selector mechanism photo-cells 99 or 100, no change is made in the speed at which the correction motor 93 operates. If when an impulse is received from the photo-cell 47 due to the passage of a register mark 45 on the web 8 the transfer cylinder 33 is at the sheet cutting position shown in Figs. 4 and 9, then the trailing end of a disc slot 97 has just passed the aperture 100 of the photo-cell 99 and the leading end of the companion disc slot 98 is just short of the aperture 102 of the photo-cell 101. This is a dead zone position, which indicates that the pre-printed web 8 is in page registry with the main webs 5 and 6 and with the cutting couple so that no adjustment in pre-printed web speed is required. If, however, at the time an impulse is received from the web scanning photo-cell 47 the disc 94 is short of the dead zone so that an impulse is also received from the photo-cell 99 and not from the photo-cell 101, this indicates that the pre-printed web 8 should be retarded to maintain page registry with the main webs and the excitation of the pilot generator is decreased, with the result that the speed of the correction motor 93 is reduced to retard the speed of the web feeder F. Similarly, if at the time the web register mark impulse is received from the photo-cell 47 the disc 94 has advanced slightly beyond the dead zone so that an impulse is also received from the photo-cell 101 and not from the photo-cell 99, this indicates that the pre-printed web should be accelerated to advance into page registry and the excitation of the pilot generator 95 is increased and the speed of the correction motor 93 accordingly increased to accelerate the web 8 through the feeder F.

Despite such acceleration or retardation of the pre-printed web 8 as may be required to maintain page registry, the web 8 is maintained under proper tension at all times due to the fact that the peripheral velocity of the transfer cylinder 33 is slightly greater than the highest linear velocity attained by the web 8, and this is accomplished, as explained above, by making the periphery of the transfer cylinder slightly longer than twice the standard page forming sheet length at which the pre-printed web 8 was originally printed. The pins 55, 56 of the transfer cylinder 33 merely tear small slots 111 (Fig. 7) in the leading margins of the page forming sheets of the pre-printed web, and these slots increase in length when the web 8 is retarded and decrease in length when this web is accelerated.

As each sheet is cut from the pre-printed web 8, its leading end is pierced by the pins 62 on the collecting cylinder and the sheet is accordingly carried around the surface of the collecting cylinder superimposed upon the main web 5. When the pins 62 reach the point of tangency with the sec-

ond main web 6, they also pierce this web and they subsequently tear out of all three webs, as shown in Fig. 6, to form tabs of the superimposed webs, as indicated at 110 in Fig. 6, thus effectively locking the inserted sheet in position with relation to the main webs.

The above-described apparatus is capable of inserting sheets cut from pre-printed webs having page forming sheet lengths slightly shorter than the page forming sheet lengths of the main webs. The majority of newspapers are printed at page forming sheet lengths of $22\frac{3}{4}$ or $23\frac{1}{2}$ inches, but most multi-color presses print at sheet lengths of approximately $21\frac{1}{2}$. When it is necessary to thus combine short pre-printed web sheets with longer main web page forming sheet lengths, the apparatus described above may be used, employing the above-described relation between the peripheral length of the transfer cylinder 33 and the maximum length of pre-printed web delivered thereto during each revolution thereof, while operating the collecting cylinder 16 at a peripheral velocity equal to the linear velocity of the main web or webs. Thus, the transfer cylinder 33 will have sheet carrying peripheral portions that are approximately one-quarter of one percent to one and one-half percent longer than the page forming sheet lengths of the pre-printed web 8 as originally printed and before elongation or shrinkage has occurred. With short pre-printed web sheet lengths, this may result in a peripheral velocity of the transfer cylinder which is less than the linear velocity of the main webs. The peripheral surface of the collecting cylinder 16 moves at a speed equal to the linear velocity of the main webs, which, in the case described, will be a slightly higher peripheral velocity than that of the transfer cylinder 33, although the transfer and collecting cylinders turn at corresponding angular velocities, that is, the collecting cylinder makes two revolutions for each revolution of the transfer cylinder. Thus, with the short sheet pre-printed web, the pins 55 and 56 of the transfer cylinder 33 maintain the pre-printed web 8 under tension until each sheet is cut therefrom, and as each cut sheet is taken off onto the collecting cylinder 16 by the pins 62, this sheet is accelerated to the main web speed at which the surface of the collecting cylinder moves.

In Figs. 11 and 12 I have illustrated a modified arrangement in which the pre-printed web may be cut longitudinally into two portions and one superimposed upon the other so as to insert into engagement with the main webs superimposed pre-printed sheets rather than a single pre-printed sheet. In this modification, parts corresponding to those of the previously described construction are designated by like reference characters having distinctive exponents. The pre-printed web 8', here illustrated as a full width web, is fed by the feeder F', which is driven from the main web press drive through a differential gearing unit 39', which regulates the pre-printed web speed to maintain page registry in the manner described above, employing for this purpose a selector mechanism L', a pilot generator 95', a control panel 96' and a correction motor 93'.

The pre-printed web 8' emerging from the feeder F' passes under the roller 115 and over the roller 116 where it is longitudinally slit into two parts 8'' and 8''' by the slitter wheel 117. The part 8'' passes around the roller 118 and around the adjustable compensating roller 119,

around the guide roller 120, and over the guide roller 121, where the other part 8''' of the pre-printed web is superimposed on the part 8''. The pre-printed web part 8''' passes down over a diagonal turning bar 122 and up over a parallel turning bar 123 and then to the roller 121, where it is superimposed on the pre-printed web part 8''. From the roller 121, the superimposed web parts 8'' and 8''' pass under the scanner S', around the guide roller 32' and onto the surface of the transfer cylinder 33', where the superimposed web parts are cut into superimposed sheets that are inserted between the main webs 5' and 6' by the collecting cylinder 16' in the manner described above in connection with the mechanism of Figs. 1-10. The compensating roller 119 is initially adjusted in a known manner to a position in which the parts 8'' and 8''' of the pre-printed web 8' are in page registry when they are superimposed at the roller 121. Aside from the sub-division of the parts of the pre-printed web 8', the modification of Figs. 11 and 12 operates in the same manner as described above in connection with the apparatus of Figs. 1 through 10.

I claim:

1. Apparatus for successively cutting page forming sheets from a moving pre-printed web for transfer into page registering contact with at least one moving main web comprising variable speed web feeding means for advancing a pre-printed web, a rotary transfer cylinder receiving the pre-printed web from said web feeding means, web piercing means on the peripheral surface of said transfer cylinder for engaging the web fed thereto by said web feeding means; a cutting cylinder adjacent said transfer cylinder cooperating therewith to cut sheets from the pre-printed web as it is led around the surface of said transfer cylinder by said web piercing means, means for varying the speed of said web feeding means and means for driving said transfer cylinder at a peripheral velocity in excess of the highest linear velocity at which the pre-printed web is fed by said web feeding means.

2. Apparatus for successively cutting page forming sheets from a moving pre-printed web for transfer into page registering contact with at least one moving main web comprising main web feeding means, variable speed pre-printed web feeding means for advancing a pre-printed web, a rotary transfer cylinder receiving the pre-printed web from said pre-printed web feeding means, web piercing means on the peripheral surface of said transfer cylinder for engaging the web fed thereto by said pre-printed web feeding means, a cutting cylinder adjacent said transfer cylinder cooperating therewith to cut sheets from the pre-printed web as it is led around the surface of said transfer cylinder by said web piercing means, means for varying the speed of said pre-printed web feeding means and means for driving said transfer cylinder at a peripheral velocity in excess of the highest linear velocity at which the pre-printed web is fed by said pre-printed web feeding means.

3. Apparatus for successively cutting page forming sheets from a moving pre-printed web for transferring them into page registering con-

taet with at least one main web comprising, main web feeding means, pre-printed web feeding means, a variable speed driving connection between said main and pre-printed web feeding means, a rotary transfer cylinder receiving the pre-printed web from said pre-printed web feeding means, web piercing pins on the peripheral surface of said transfer cylinder for engaging the pre-printed web and carrying it along such surface, a rotary cutting cylinder adjacent said transfer cylinder and cooperating therewith to cut sheets from the pre-printed web carried on said transfer cylinder, means for transferring the sheets so cut from said transfer cylinder into contact with the main web, means for varying said variable speed driving connection and means for driving said transfer cylinder at a peripheral velocity in excess of the highest linear velocity at which the pre-printed web is fed by said pre-printed web feeding means.

4. Apparatus for successively cutting page forming sheets from a moving pre-printed web and transferring them into page registering contact with at least one main web comprising, main web feeding means, pre-printed web feeding means, a variable speed driving connection between said main and pre-printed web feeding means, a rotary transfer cylinder receiving the pre-printed web from said pre-printed web feeding means, web piercing pins on the peripheral surface of said transfer cylinder for engaging the pre-printed web and carrying it along such surface, a rotary cutting cylinder adjacent said transfer cylinder and cooperating therewith to cut sheets from the pre-printed web carried on said transfer cylinder, means for transferring the sheets so cut from said transfer cylinder into contact with the main web, means for varying the variable speed driving connection, and driving means for rotating said transfer cylinder in page synchronism with the speed at which the main web is fed by said main web feeding means, said transfer cylinder having a periphery longer than the maximum length of pre-printed web fed by said pre-printed web feeding means during each revolution of said transfer cylinder, whereby the pre-printed web is maintained in tension on said transfer cylinder despite variations in the speed of said pre-printed web feeding means.

5. Apparatus for successively cutting page forming sheets from a moving pre-printed web and transferring them into page registering contact with at least one main web comprising, main web feeding means, pre-printed web feeding means, a variable speed driving connection between said main and pre-printed web feeding means, a rotary transfer cylinder receiving the pre-printed web from said pre-printed web feeding means, means for driving said transfer cylinder in timed relation to said main web feeding means, web piercing pins on the peripheral surface of said transfer cylinder for engaging the pre-printed web and carrying it along such surface, a rotary cutting cylinder adjacent said transfer cylinder and cooperating therewith to cut sheets from the pre-printed web carried on said transfer cylinder, means for transferring the sheets so cut from said transfer cylinder into contact with the main web, and means for varying said variable speed driving connection, said transfer cylinder having a periphery longer than the maximum length of pre-printed web fed by said pre-printed web feeding means during each revolution of said transfer cylinder, whereby the pre-printed web

is maintained in tension on said transfer cylinder despite variations in the speed of said pre-printed web feeding means.

6. Apparatus for successively cutting page forming sheets from a moving pre-printed web and transferring them into page registering contact with at least one main web comprising, main web feeding means, pre-printed web feeding means, a variable speed driving connection between said main and pre-printed web feeding means, a rotary transfer cylinder receiving the pre-printed web from said pre-printed web feeding means, web piercing pins on the periphery of said transfer cylinder for engaging the pre-printed web and carrying it along such periphery, a rotary cutting cylinder adjacent said transfer cylinder and cooperating therewith to cut sheets from the pre-printed web carried on said transfer cylinder, means for transferring the sheets so cut from said transfer cylinder into contact with the main web, means responsive to the relative positions of page forming sheet lengths of the pre-printed web and the main web for varying said variable speed driving connection to maintain said webs in page registry, and means for driving said transfer cylinder at a peripheral velocity in excess of the highest linear velocity at which the pre-printed web is fed by said pre-printed web feeding means.

7. Apparatus for successively cutting page forming sheet lengths from a moving pre-printed web and transferring them into page registering contact with at least one main web comprising, in combination with means for printing pages on successive page forming sheet lengths of at least one main web and a pre-printed web having pages pre-printed on successive page forming sheet lengths thereof, main web feeding means, pre-printed web feeding means, a variable speed driving connection between said main and pre-printed web feeding means, a rotary transfer cylinder receiving the pre-printed web from its feeding means, web piercing pins on the peripheral surface of said transfer cylinder for engaging the pre-printed web and carrying it along such surface of said transfer cylinder, a cutting cylinder adjacent said transfer cylinder and cooperating therewith to cut a whole number of page forming sheet lengths from the pre-printed web during each revolution of said transfer cylinder, means for transferring sheets so cut from said pre-printed web into contact with said main web, means for driving said transfer cylinder in timed relation to said main web feeding means, and means responsive to the relation between the rate of page travel of said pre-printed web and the rate of rotation of said transfer cylinder for varying said variable speed driving connection to said pre-printed web feeding means whereby said pre-printed web is maintained in page registry with said main web, said transfer cylinder having a periphery longer than the maximum length of said pre-printed web fed by the pre-printed web feeding means during each revolution of said transfer cylinder, whereby said pre-printed web is maintained in tension on said transfer cylinder despite variations in the speed at which said pre-printed web is fed.

8. Apparatus for successively cutting page forming sheets from a moving pre-printed web and transferring them into page registering contact with at least one main web comprising, main web feeding means, pre-printed web feeding means, a variable speed driving connection between said main and pre-printed web feeding means, a rotary transfer cylinder receiving the

pre-printed web from said pre-printed web feeding means, web piercing pins on the peripheral surface of said transfer cylinder for engaging the pre-printed web and carrying it along such surface, a rotary cutting cylinder adjacent said transfer cylinder and cooperating therewith to cut sheets from the pre-printed web carried on said transfer cylinder, means for varying the variable speed driving connection, said transfer cylinder having a periphery longer than the maximum length of pre-printed web fed by said pre-printed web feeding means during each revolution of said transfer cylinder, whereby the pre-printed web is maintained in tension on said transfer cylinder despite variations in the speed of said pre-printed web feeding means, a rotary collecting cylinder having a portion of its cylindrical surface parallel to and adjacent the surface of said transfer cylinder, web piercing pins on the surface of said collecting cylinder movable to engage a pre-printed web sheet on said transfer cylinder, means for conducting at least one main web fed by said main web feeding means into contact with the cylindrical surface of said collecting cylinder at a point where it approaches the surface of said transfer cylinder whereby said collecting cylinder pins pierce said main web and pierce a pre-printed sheet, and subsequently tear out of said pre-printed sheet and said main web during further rotation of said collecting cylinder to form tabs in said sheet and web which secure the sheet to the web.

9. Apparatus for successively cutting page forming sheets from a moving pre-printed web, the page forming sheet length of which varies from the standard sheet length at which it was originally printed, for transfer into page registering contact with a moving main web of standard page forming sheet length comprising, main web feeding means, variable speed pre-printed web feeding means for advancing the pre-printed web, a rotary transfer cylinder receiving the pre-printed web from said pre-printed web feeding means, web piercing means on the peripheral surface of said transfer cylinder for engaging the web fed thereto by said pre-printed web feeding means, a cutting cylinder cooperating with said transfer cylinder to cut sheets from the pre-printed web on the surface of said transfer cylinder, means for varying the speed of said pre-printed web feeding means, and driving means for rotating said transfer cylinder in page synchronism with the speed at which the main web is fed by said main web feeding means, said transfer cylinder having page forming sheet car-

rying portions occupying its entire periphery and each longer than the standard page forming sheet length at which the pre-printed web was originally printed, whereby the pre-printed web is maintained under tension on said transfer cylinder despite variations in the speed of said pre-printed web feeding means.

10. Apparatus for successively cutting page forming sheets from a moving pre-printed web, the page forming sheet length of which varies from the standard sheet length at which it was originally printed, for transfer into page registering contact with a moving main web of standard page forming sheet length comprising, main web feeding means variable speed pre-printed web feeding means for advancing the pre-printed web, a rotary transfer cylinder receiving the pre-printed web from said pre-printed web feeding means, web piercing means on the peripheral surface of said transfer cylinder for engaging the web fed thereto by said pre-printed web feeding means, a cutting cylinder cooperating with said transfer cylinder to cut sheets from the pre-printed web on the surface of said transfer cylinder, means for varying the speed of said pre-printed web feeding means and driving means for rotating said transfer cylinder in page synchronism with the speed at which the main web is fed by said main web feeding means, said transfer cylinder having page forming sheet carrying portions occupying its entire periphery that are from about one-quarter of one percent to one and one-half percent longer than the standard page forming sheet length at which the pre-printed web was originally printed, whereby the pre-printed web is maintained under tension on said transfer cylinder despite variations in the speed of said pre-printed web feeding means.

PAUL L. TOLLISON.
